ATTORNEYS

UNITED STATES PATENT OFFICE.

AUSTIN F. JACKSON, OF TAUNTON, MASSACHUSETTS.

DESIGN FOR A SPOON, &c.

SPECIFICATION forming part of Design No. 21,300, dated January 19, 1892.

Application filed December 5, 1891. Serial No. 414,172. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons, Knives, Forks, Ladles, &c., of which the following is a specification, reference being had to the accompanying drawing, showing a part thereof.

The figure is a front face or upper side view of a coffee-spoon having my design applied to it.

The leading feature of my design is a rep-

resentation of a spray of golden rod *a*, applied to and forming the main body portion of the handle. A cluster of blossoms *b* is disposed at the bottom of the spray or between it and the shank of the handle. The outer edges of the spray and blossoms give their contour to and form the outer margin of the handle.

What I claim is—

The design for a spoon - handle, as herein shown and described.

AUSTIN F. JACKSON.
